ADELE WEISS AND EMANUEL WEISS, OF PASADENA, CALIFORNIA.

ADJUSTABLE RECEIVER-HOLDER.

1,329,942.

Specification of Letters Patent. Patented Feb. 3, 1920.

Application filed December 5, 1918. Serial No. 265,440.

To all whom it may concern:

Be it known that we, ADELE WEISS and EMANUEL WEISS, citizens of the United States, residing at Pasadena, in the county 5 of Los Angeles and State of California, have invented new and useful Improvements in Adjustable Receiver-Holders, of which the following is a specification.

This invention relates to adjustable telephone receiver holders, and consists of the 10 novel features herein shown, described and claimed.

Our object is to make a device which may be readily applied to a wall telephone or 15 to a desk telephone to hold the receiver in position for use, and at the same time operate the receiver hook as required to operate the telephone.

A further object of this invention is to 20 provide a suitable stand for supporting a telephone, pivot an arm to the stand, mount the telephone receiver upon the arm and provide a connection between the pivoted arm and the receiver hook, so that when the arm is tipped one way the receiver is in position for use, and so that when the arm is tipped the other way the receiver hook is held down, the same as though the receiver were hung upon the hook.

30 Figure 1 is a perspective showing an adjustable telephone receiver holder embodying the principles of our invention in connection with a desk telephone.

Fig. 2 shows a modified form of base as 35 required to adapt the adjustable telephone receiver holder to a wall telephone.

Fig. 3 is a plan view of the base shown in Fig. 1.

Fig. 4 is an edge view of the base shown 40 in Fig. 3.

Fig. 5 is a side elevation of the pivoted arm.

Fig. 6 is a side elevation of the adjustable extension of the pivoted arm.

45 Fig. 7 is a fragmentary side elevation at right angles to Fig. 6, and showing the telephone receiver mounted in the extension of the pivoted arm.

Fig. 8 is a fragmentary sectional elevation 50 showing the mounting of the pivoted arm and the sliding connection between the extension and the pivoted arm.

Fig. 9 is a side elevation of the trip

mounted upon the pivoted arm for operating the receiver hook of the telephone. 55

Fig. 10 is a plan view of the trip shown in Fig. 9.

Fig. 11 is a perspective of the modified form of base for supporting the pivoted arm for a wall telephone, as shown in Fig. 2. 60

The base 1 is preferably formed of wood, is circular in plan and flat in elevation, and has a lower face 2 adapted to rest upon a desk, and a circular depression 3 formed from its upper face to receive the bottom of the stand 4 of a desk telephone. The bottom 4 may be glued or otherwise fixed in the depression 3. An abutment 5 is formed integral with the base 1 and extends laterally upon the level of the base. One member 6 of a butt hinge is placed on top of the abutment 5, a rubber buffer 7 is placed upon the member 6, and a screw 8 is inserted downwardly through the buffer 7, through the member 6 into the abutment 5, and other 75 screws 9 are inserted through the member 6 into the abutment 5 to hold the member 6 securely in place. The abutment 5 has an outer inclined face 10 substantially in line with the hinge pin 11. The pivoted arm 80 12 is secured to the other member 13 of the hinge by screws 14, so that the lower side face 15 of the pivoted arm will fit against the inclined face 10 of the abutment 5 when the receiver holder is in position to use the 85 telephone. A shoulder 16 is formed upon the pivoted arm 12 in position to engage the buffer 7 when the pivoted arm is thrown backwardly to put the telephone out of use.

A straight bore 17 is formed in the pivoted 90 arm 12 from its upper end, and the adjustable extension 18 is mounted in the bore.

The adjustable extension 18 consists of a socket 19 adapted to hold the telephone receiver 20, the stem 21 extending from the 95 socket 19, an adjustable piece 22, the adjusting screw 23 mounted in the piece 22 and screw seated in the stem 21, so that by rotating the piece 22 it may be moved to or from the stem 21, and the spring loop 24 100 having its ends attached to the sides of the piece 22. The stem 21 and the piece 22 fit loosely in the bore 17, and the spring loop 24 engages the wall surface around the bore, so that when the piece 22 is properly 105 adjusted relative to the stem 21 and the

stem carrying the loop 24 is inserted downwardly into the bore 17, the socket 19 may be adjusted up and down to lengthen or shorten the effective length of the pivoted arm 12, and the tension of the spring loop 24 will hold the socket to hold the receiver 20 in its adjusted position. In order that the screw 23 will not wear the wood of the stem 21, a nut 25 is embedded into the end 10 of the stem. The screw 23 and nut 25 are principally designed to form a swivel connection between the receiver 20 and the stand base 1, so that in rotating the receiver 20 to a convenient position, the spring loop 24 need not be rotated in the bore 17. Usually the adjustment of the effective length 15 of the stem 21 will be obtained by moving the stem up and down in the bore 17, and it will not be necessary to rotate the piece 22 except for swiveling purposes after the parts have been properly assembled.

The stem of the telephone receiver 20 is tapered and the socket 19 has a tapered opening 26 to fit the stem of the receiver 20, and a slot 27 leads sidewise to the opening 26, so that the small part of the receiver 20 will pass through the slot and then the receiver may be moved endwise until it tightens in the opening 26.

30 The upper portion of the pivoted arm 12 is tapered slightly and the clip 28 has a central opening 29 to receive the tapered portion of the pivoted arm 12, so that the clip will tighten upon the arm. The trip 30 is 35 rigidly fixed to the central portion of the clip 28 and extends backwardly in a substantially horizontal position. The trip 30 comprises a finger 31 adapted to pass over and press downwardly upon the receiver hook 32 40 of the telephone, a central portion 33 bent at right angles to the finger 31 and forming a shoulder to engage the receiver hook, and an arm 34 bent at right angles to the central portion 33 and secured to the clamp 28.

45 When it is desired to apply the adjustable telephone receiver holder to a desk telephone 35, the bottom of the stand 4 is placed in the depression 3 of the base 1, the base rotated relative to the stand 4 to 50 bring the pivoted arm into a convenient position to swing to and from the receiver hook 32, the clip 28 is loosened and rotated upon the pivoted arm 12 to bring it into position to engage the telephone receiver hook 32, the receiver 20 is placed in the 55 socket 19, the extension 18 is adjusted up and down to bring the receiver into convenient position for the ear of the operator and the extension 18 is rotated to bring the receiver 60 into the proper angle and the device is ready for use.

When it is desired to use the telephone, the user will grasp the pivoted arm 12 and pull it forwardly, thus releasing the trip 65 30 from the receiver hook 32, and then the

user's hands are free for writing or other purposes while the telephone is being used.

One of the principal objects of our invention is to provide means whereby both hands of the operator are free while using 70 a telephone.

In the modifications shown in Figs. 2 and 11, the bracket 36 is adapted to be secured directly to the wall 37 supporting the wall telephone 38. The base 39 is secured to the 75 bracket 36 and is secured to the wall 37 by screws or nails 40. The pivoted arm 12 is secured to the base 39 in the same way that it is secured to the base 1, and the bracket 36 carrying the base 39 is located so as to 80 bring the arm 12 into proper relation to the telephone 38, so that the trip 30 will engage the telephone receiver hook 41 to hold the hook down when the telephone is out of use, and to release the hook when it is desired to talk over the telephone.

Thus we have produced an adjustable telephone receiver holder the use of which leaves both hands of the operator free while telephoning.

Various changes may be made without departing from the spirit of our invention as claimed.

We claim:

1. In an adjustable telephone receiver holder, a pivoted arm having a bore extending from its upper end, a receiver socket, a stem extending from the receiver socket into the bore, a piece swiveled to the lower end of the stem in the bore, and means for 95 forming a friction connection to hold the piece in an adjusted position in the bore.

2. In an adjustable telephone receiver holder, a pivoted arm having a bore extending from its upper end, a receiver socket, a stem extending from the receiver socket into the bore, an adjustable piece, a screw mounted in the adjustable piece and screw seated in the stem so that by rotating the adjustable piece it may be moved to or from 105 the stem, and means forming a friction connection to hold the piece in an adjusted position in the bore.

3. In an adjustable telephone receiver holder, a pivoted arm having a bore extending from its upper end, a receiver socket, a stem extending from the receiver socket into the bore, an adjustable piece, a screw mounted in the adjustable piece and screw seated in the stem so that by rotating the adjustable piece it may be moved to or from the stem, and a spring loop having its ends attached to the sides of the piece and forming a friction connection to hold the piece in 115 an adjusted position in the bore.

4. In an adjustable telephone receiver holder, a base, an abutment formed integral with the base and extending laterally, a hinge connected to the upper face of the abutment, a rubber buffer connected to the 120 125 130

upper face of the abutment, said abutment having an outer inclined face in line with the hinge pin, a pivoted arm secured to the hinge and having a face adapted to engage 5 the inclined face of the abutment, a shoulder formed upon the pivoted arm in position to engage the buffer, there being a straight bore extending from the upper end

of the pivoted arm, a socket, a stem extending from the socket, and means for adjusting 10 the stem in the socket.

In testimony whereof we have signed our names to this specification.

ADELE WEISS.
EMANUEL WEISS.
